UNITED STATES PATENT OFFICE.

HUGO NEUMAN, OF FORD CITY, ONTARIO, CANADA, ASSIGNOR TO DIAMOND MANUFACTURING COMPANY, OF DETROIT, MICHIGAN, A CORPORATION OF MICHIGAN.

MACHINE FOR FORMING METAL TUBES.

1,257,293.

Specification of Letters Patent. Patented Feb. 19, 1918.

Application filed March 20, 1914. Serial No. 825,990.

To all whom it may concern:

Be it known that I, Hugo Neuman, a citizen of the United States of America, residing at Ford City, in the Province of Ontario and Dominion of Canada, have invented certain new and useful Improvements in Machines for Forming Metal Tubes, of which the following is a specification, reference being had therein to the accompanying drawings.

The invention relates to tube-forming machines, and has for its object the obtaining of a construction adapted for the manufacture of channeled tubes, such as are used for wind-shield frames and for similar purposes. It is a further object to form the tubes from a plurality of flat strips of sheet metal, which are separately formed to the desired cross section and then united and seamed together.

In the drawings:

Figure 1 is a front elevation of the machine;

Figs. 2 to 8 inclusive are cross sections of the main blank in various stages of formation;

Figs. 9 and 10 are end elevations of the dies;

Figs. 11 to 15 inclusive are similar views illustrating the progressive formation of the auxiliary blank;

Figs. 16, 17 and 18 are similar views showing the operations of seaming the two blanks together to form the completed tube;

Fig. 19 is a cross section through one of the bearings for the shaft of the forming roll showing the adjustment and tensioning means; and

Fig. 20 is a cross section through the completed tube.

A is a suitable frame, upon which are mounted pairs of forming rolls arranged in series and adapted to successively operate upon a sheet metal blank. All or a part of these rolls are positively driven by suitable mechanism, not shown, and the individual rolls are exchangeable to form strips of different contour. As shown in Figs. 2 to 10 inclusive, the flat strip B is first fed between flat rolls C C', and then passes to the first pair of forming rolls D D', which bend it into a slightly reversely-curved cross section, illustrated in Fig. 3. The strip next engages a pair of forming rolls E E' which bend it into the section shown in Fig. 4 and

then is successively operated upon by the pairs of forming rolls F F', G G', H H', I I', which progressively fashion it, as illustrated in Figs. 5 to 8. It will be observed that in these successive operations a channel strip is formed, having its opposite edges provided with reversely-bent flanges.

J is a reel, preferably mounted upon the frame A and carrying a coil of previously-formed strip, which is complementary to the main strip in forming the tube. This complementary strip is preferably formed upon the same machine by an exchangeable set of rolls, illustrated in Figs. 11 to 15, which progressively fashion the cross section from the flat to a U-shaped channel having reverse-bent flanges. The strip K thus fashioned is wound upon the reel J, from which it is fed into engagement with the strip B. Before, however, the two strips come into engagement, the strip B passes from the rolls I and I' through stationary forming dies L and M, shown respectively in Figs. 9 and 10, the former deepening the channel and the latter bending the edge portions inward and the intermediate portion into the segment of a circle. Thus when fed from the die M, the flanges or hooks a of the strip B will pass into the reverse-bent hooks b of the strip K, as shown in Fig. 16, this being performed while the strips are passing through stationary dies N. From this point the strip is fed to a pair of rolls O O', which, as shown in Fig. 17, initiate the closing of the seam, while the pair of rolls P P', together with an intermediate roll P², complete the seaming operation. The rolls such as O and O' are driven in timed relation to the fastening rolls I and I', etc., by any suitable driving mechanism such as the sprocket and chain drive shown in Fig. 2. The invention, however, is not directed to any specific construction of driving mechanism.

The tube when delivered from the machine is of the section shown in Fig. 20, the outer member being the segment of a circle and the inner member of a U-shape, while the two members are united by a seam or bead. The operation may be performed continuously, and as the strip K is fed through its engagement with the strip B the two will be united to form a straight tube. It has been found, however, that where sheet metal strips are fed between complementary rolls hav-

ing a fixed space therebetween, slight irregularities in the gage of the metal will cause a drawing at one point more than at another, which will result in bending or warping the strip. This is avoided in my construction by a yieldable and adjustable bearing for the forming rolls, illustrated in Fig. 19. This bearing comprises an eccentric sleeve *Q* in which the shaft *R* of one of the rolls is journaled, said sleeve being rotatively adjustable by a lever or handle *S*. When the lever or handle *S* is adjusted in one direction, it will, by the cam action of the eccentric sleeve *Q*, force the shaft *R* away from the other shaft of the pair, while adjustment of the handle *S* in the opposite direction will, by reverse cam action, decrease the distance between the two shafts. The levers *S* are each adjusted by hand and locked by set screws as shown in Fig. 1. *T* is a bearing block for the sleeve *Q*, which is yieldably held in position by a spring *U* which engages a recess in said block and bears against an abutment *V*, which is adjustable by a screw *W* passing through a cap *X*. The arrangement is such that by proper adjustment of the screw *W*, the ten-

sion of the spring *U* may be so adjusted that the eccentric sleeve *Q* is permitted to yield so as to avoid drawing and warping the metal of the strip. On the other hand the tension is sufficient to produce the necessary frictional engagement between the rolls and the strip, so that the latter will be formed to the proper contour. 35

What I claim as my invention is;—

The combination with a frame, of a series of pairs of forming rolls mounted on said frame and adapted to progressively fashion a sheet metal strip, seaming rolls arranged in alinement with said series of rolls, stationary forming dies between said series of rolls and seaming rolls, and means for delivering a complementary fashioned strip to said intermediate dies into engagement with 40 the strip fed from said series of rolls, whereby said seaming rolls will unite the engaged strips. 45

In testimony whereof I affix my signature in presence of two witnesses.

HUGO NEUMAN.
